CARBOY PACKAGE

Richard W. Lahey, New Rochelle, N. Y., and Kenneth M. Sieg, Elizabeth, N. J., assignors to American Cyanamid & Chemical Corporation, New York, N. Y., a corporation of Delaware

Application October 23, 1934, Serial No. 749,534

5 Claims. (CL 217—52)

The present invention relates to a boxed carboy, that is, a crate or case within which is located a frangible container, usually a bottle, ordinarily used for the shipping of liquid materials.

In such boxed carboys, it is customary to provide cushions of one kind or another between the bottle and the box to absorb shocks and prevent breakage. A considerable amount of work has been done to arrive at a combination which will increase the life of the package as a whole and prevent undue breakage of the bottle.

Much effort has also been expended looking toward the choice of suitable materials to act as cushioning means between the bottle and the box or case which, of course, is important although it is not believed sufficient attention has been paid to the actual constructional details of the box and/or its associated parts.

20 The effectiveness of carboy packings is usually determined by filling a packed carboy with water, placing the same in a cradle hung from an overhead support, the cradle resting against a concrete slab or block, swinging the cradle and carboy out from the concrete block a considerable distance and then releasing the cradle. As to whether or not the package will withstand the shock of the impact over different distances has been accepted as the standard test of efficiency.

30 We have conducted a series of experiments including swing tests with various types of packings and have studied the action and reaction of such packings under impact by means of the slow motion picture camera. As a result of these observations, we have found that both the bottle and the box have certain tendencies which must be taken into consideration if an effective packing is to be had. With the combination of this invention, we have made the following swing tests on the same bottle and packing without shattering or dislodging the bottle:

10 times from 75 inches

1 time from 85 inches

1 time from 95 inches

45 2 times from 105 inches

On another similar carboy package, the successful swings were:

1 time from 75 inches

.1 time from 85 inches

50 1 time from 95 inches

3 times from 105 inches

The invention, therefore, contemplates broadly a packed carboy which includes a box and a bottle therein with cushion members between the box and the bottle, cushion carriers for holding the

cushions in a manner which will permit of the rocking of the cushion carriers and consequently slight relative movement of the cushions with respect to both the bottle and the box. The invention further contemplates separation means between the cushion carriers and the corner posts of the box which serves not only as a positive location means to center the cushion carriers properly but which also permits of this desirable rocking action above referred to. These separation means may be shims or wedges to put the cushion members under compression.

The invention further contemplates the use of a greater degree of pressure on one set of cushions than another, all for a purpose more fully hereinafter described.

The invention further consists in the details of construction, combination and arrangement of parts more fully hereinafter described and with reference to the accompanying drawings which are to be illustrative only and not in a limiting sense.

In the drawings, Fig. 1 is a sectional plan view through a packing of this invention;

Fig. 2 is a sectional elevation along the line 25 2—2 of Fig. 1;

Fig. 3 is a sectional view along the line 3—3 of Fig. 1;

Fig. 4 is a perspective view of a cushion carrier; and

Fig. 5 is a rear view of the cushion carrier of Fig. 4.

Referring now with particularity to the embodiments illustrated, a box or casing is shown generally at 1, consisting of four sides and bottom with hand holds 2 and skids 3, all of which are of usual construction.

Within each corner of the box is a substantially triangular corner post 4 having a vertical groove 5 therein for a purpose to be more fully hereinafter described.

Seated on the bottom of the box are cross pieces 6 and 7 carrying cushions 8, upon which the bottom of the bottle rests. It is preferred that these bottom cushions 8 engage the bottle bottom at an area including definite curvature as shown in Fig. 3 as this makes for effectiveness and tends to prevent lateral displacement under shock.

The bottle is shown generally at 9 and may be of any desired configuration.

Between the bottle and the box, there are located an upper and lower series of cushions 10 and 11 respectively. Each of these cushions is held in a groove in a cushion carrier 12 and secured thereto in any desired manner as by means

of a cement or the like. It is to be noted that the plane of the area of contact between the cushion and the cushion carrier is at an angle to the vertical so that the cushions 10 and 11 likewise engage the bottle surface at an angle. 5 This makes the imaginary lines of compression of the top and bottom series of cushions at an angle to each other so that they intersect when extended. The rear face of each cushion carrier 12 is grooved as at 13, that groove being substantially of the same extent as groove 5 in the corner post 4. A spacing member 14 engages with the corner post 4 and the cushion carrier 12 in their respective grooves. It is to be understood that 10 each spacing or separation member 14 is of a vertical extent sufficient to engage both an upper and a lower cushion carrier. These members 14 may be either shims or wedges as the case may be, although we prefer the latter as it insures the 15 use of a greater degree of compression on the top cushions than on the bottom cushions.

Where found desirable, joining members 18 may be used to connect the upper and lower cushion carriers.

25 A top 16 having an aperture therein may be used to secure the bottle in the box with suitable neck-protecting devices as is usual in this art.

It is believed that the material of which the 30 cushions are to be made is important. In this connection, reference is made to the co-pending application of Lahey and Kast, Serial No. 721,356, filed April 19, 1934. There is disclosed the use of unvulcanized, reclaimed rubber cushions having high shock absorbing capacity, slow 35 recoil and high aging-resisting abilities, these characteristics remaining substantially constant at temperatures ranging between 0° and 100° F. The use, therefore, of uncured whole tire reclaimed rubber having a plasticity figure varying 40 between 2.80 and 3.80 based in a $\frac{1}{4}$ inch base point under 1 kilogram load for one minute as measured in a Pusey-Jones Plastometer, is preferred for the cushions, in the combination of this invention. Such cushion material is not 45 absolutely necessary, however, inasmuch as the packing herein described has relieved the cushion of much of its responsibility for the bottle behavior. The invention, therefore, is not dependent upon the use of any particular cushion material although the above material is preferred 50 as undoubtedly such a cushion does contribute materially to the total effect desired.

A study of slow motion pictures, particularly 55 those of the package at the moment of impact and slightly thereafter show conclusively that the entire bottle has a tendency to move in the direction of the swing upon impact as would be expected, and that unless limited movement is permitted, the bottle will shatter. For this reason, 60 unless substantially the constitutional combination herein shown and described is used, such cushions as block cork or asphalt-coated cork agglomerates are not efficient. Block cork as a cushion material is not particularly efficient for 65 the reason that its rate of compressibility is too slow and, hence, does not permit desirable bottle movement. Asphalt-coated agglomerates are likewise objectionable because at low temperatures the asphalt becomes brittle and at high 70 temperatures its adhesive qualities are lessened. Under these circumstances, the bottle may shatter either because it strikes the side of the box or because of resistance to movement. There must, therefore, be limited bottle movement permitted 75 at the moment of impact and the combination

herein referred to is admirably adapted for that purpose as it permits just the right amount of movement with sufficient recoil and insures the automatic return of the bottle to its proper position with relation to the rest of the assembly. 5

All parts of the box, in the same manner, have a tendency to move in the direction of swing following impact. It has been customary in the past to drive shims between the box corner posts and the cushions where those shims have a contact area with the corner post substantially equal to that of the corner post with no positive interlock therebetween. As a result thereof, when such boxes are swung, the slow motion picture camera records an actual displacement of such 15 shims from the corner post with no positive way of returning them to their proper position upon recoil. As a result, two or three swings of such a box may so entirely displace the shims as to render them ineffective, which loosens the cushion 20 and renders the entire packing inefficient. On the other hand, by tonguing and grooving the separation members 14, which may be either shims or wedges, both to the corner post and the cushion carriers, in combination with the 25 lengthened cushion carriers, at no time do these three members lose their relationship. While they may, immediately following impact, move away from each other, yet the grooves in those members are deep enough so that the parts 14 do not leave them and are immediately returned to their proper position upon recoil.

In this momentary displacement of the cushion carriers and the separation members, at or immediately following impact, it has been 30 found to be of advantage to permit the cushion carrier with its cushion to have a slight rocking movement. This is accomplished by reason of the fact that the separation members 14 have a contact area with the cushion carrier of a 40 relatively slight extent only. It is to be noted that the cushion carriers 12 extend in a direction toward two adjacent sides of the box although they are normally out of contact therewith. At the moment of impact in swing tests, 45 however, where the swing has been from extreme distances, the slow motion picture camera records the fact that the bevelled ends of the cushion carriers actually contact with the sides of the box which prevents further movement. 50 In other words, this combination and construction of parts is designed primarily to permit slight relative movement of the parts upon impact while limiting the extent of that movement so as not to permanently displace the parts from 55 their desired relationship.

That the cushion carriers as above described are of the floating variety is also highly desirable in that if the cushions are not adjusted exactly right when initially placed in position, 60 they may find their proper location in the course of time, making their adjustment automatic, particularly as the bottle settles.

When conducting swing tests on packed carboys from extreme distances which have caused 65 shattering of the bottle, the slow motion picture camera has recorded the fact that in most instances there is a surge of liquid within the bottle upwardly into the neck thereof and that this surge exerts sufficient force at times to completely disconnect the neck and upper part of the bottle from the body thereof. Many of the broken carboys contain the neck of the bottle in a single piece down to the juncture of the neck 70 at the shoulder. This means, of course, that 75

there is a tendency for the bottle to jump vertically upward upon impact, due to liquid surge. This may be prevented by putting a greater compression upon the upper cushions than that upon the lower and by placing the upper cushions at a point where, when under compression, they will flow over the curvature of the bottle shoulder. This situation is diagrammatically represented in Fig. 3. Due to the fact that the cushion carriers are inclined, the cushions engage the bottle at its point of greatest strength, that is, along substantially the radius of the arc of the shoulder or bottom as the case may be. This, therefore, tends to hold the bottle between the cushions vertically, although they are located at the bottle sides. By using wedges as the separation members 14, the entire set of upper cushions may be put under a compression greater than those of the lower set, which has been found to effectively resist the tendency of the bottle to jump upwardly upon impact due to liquid surge within the bottle.

From the above, it will be apparent that the invention is of particular advantage in that the packing of the carboys is much simplified and is not dependent upon hand labor to properly center the cushions, for the grooves and spacing members together with the cushion carriers automatically center the cushions on the bottle in the proper location. This combination of parts not only prevents accidental displacement of the cushions under severe shock but insures their return to the initial and effective position. Moreover, the fact that the cushion carriers and, consequently, the cushions are permitted a slight rocking movement tends to absorb shocks. Under extreme conditions of shock, the cushion carriers may contact with the sides of the box, thus distributing the shock to the box sides and corner posts with consequent saving in detrimental effect on the box or case.

It will also be apparent that the cushions engage the bottle at its strongest points with the line of pressure on the cushions following substantially that of the radius of the bottle arc with which the cushion contacts. Under these conditions, the center portion of each cushion is under the greatest pressure which causes a flow of the remainder of the cushion material towards each end of that arc. The bottle thus floats between the upper and lower cushions, the latter being automatically adjusted vertically as the bottle settles upon aging. The fact that the upper series of cushions are under a greater pressure than the lower series offers the necessary resistance to the tendency of the bottle to move upward under liquid surge.

While the invention has been shown and described with reference to particular embodiments, yet, obviously, such embodiments are to be taken

as illustrative only and the invention is to be construed broadly and restricted only by the scope of the claims.

We claim:

1. A boxed carboy comprising a box and a bottle therein, a series of cushions between the box and the bottle, a cushion carrier, a box corner post, means for forcing separation of the corner post and the cushion carrier to thereby compress the cushion, said means, carrier and corner post being tongued and grooved together. 5

2. A boxed carboy comprising a box and a bottle therein, a series of cushions between the box and the bottle, a rocking cushion carrier, a box corner post and means engaging the corner post 15 and the cushion carrier for forcing separation of those parts and thereby putting the cushion under compression, the plane of the cushion engaging face of each cushion carrier being inclined from the vertical so as to put the upper portion of 20 the upper cushion and the lower portion of the lower cushion under a compression greater than the remaining portion of said cushions.

3. A boxed carboy comprising a box and a bottle therein, a series of cushions between the box 25 and the bottle, a cushion carrier, a box corner post, the opposing faces of the cushion carrier and corner post being grooved and a separation member tongued into the grooves on the carrier and corner post. 30

4. A boxed carboy comprising a box and a bottle therein, a triangular corner post at each corner of the box containing a vertical groove, a pair of cushion carriers located generally at each corner of the box and spaced from the corner post by means of a wedging element, the wedging element being seated in a groove in one pair of the cushion carriers and a corner post, the top and bottom cushion carriers being tied together, a cushion on each cushion carrier, the plane of the face of 40 each carrier in contact with its cushion being at an angle to the vertical, the top portion of each top cushion and the bottom portion of each bottom cushion being under a compression greater than that of the remainder of those cushions, the 45 imaginary lines of pressure on the upper and lower cushions intersecting when extended.

5. A boxed carboy comprising a box and a bottle therein, a series of cushions between the box 50 and the bottle, a rocking cushion carrier, a box corner post and loosely mounted means engaging the corner post and the cushion carrier for forcing the separation of those parts and thereby putting the cushion under compression in which the area of engagement of the separation forcing means with the corner post and the cushion carrier, is less than the area of the planes with which said separation means contact. 55

RICHARD W. LAHEY. 60
